DESIGN FOR A COMBINED CIGARETTE AND JEWELRY CONTAINER

Matteo Giannillo, Brooklyn, N. Y.

Application October 29, 1946, Serial No. 134,372

Term of patent 3½ years

(Cl. D85—2)

To all whom it may concern:

Be it known that I, Matteo Giannillo, a citizen of the United States, residing in Brooklyn, county of Kings, and State of New York, have invented a new, original, and ornamental Design for a Combined Cigarette and Jewelry Container, of which the following is a specification, reference being had to the accompanying drawing, forming part thereof.

Figure 1 is a top plan view of a combined cigarette and jewelry container, showing my new design as it appears with the central cover in open position.

I claim:

The ornamental design for a combined cigarette and jewelry container, as shown.

MATTEO GIANNILLO.
